[57] CLAIM

The ornamental design for a fishing rod tube, as shown
and described.

DESCRIPTION

FIG. 1 is a side elevational view of a fishing rod tube
showing my new design, the pattern thereof being in-
corporated about the circumference of the tube, extend-
ing over the full length thereof, the fishing rod tube
being symmetrical about its axis;

FIG. 2 is a top plan view thereof, the bottom plan view
thereof being a mirror image thereof;

FIG. 3 is an enlarged end view thereof;

FIG. 4 is an end view thereof taken from the opposite
end shown in FIG. 3;

FIG. 5 is an enlarged view of a portion of the tube
shown in FIG. 1 at V;

FIG. 6 an enlarged view of a portion of the tube of FIG.
1 as shown at VI.
